(57) **CLAIM**

The ornamental design for a housing with interface panel for a pressure source, as shown and described.

DESCRIPTION

FIG. 1 is a left, front perspective view of a housing with interface panel for a pressure source in accordance with the present invention;

FIG. 2 is a left, rear view of the housing with interface panel for a pressure source illustrated in FIG. 1;

FIG. 3 is a rear perspective view of the housing with interface panel for a pressure source illustrated in FIG. 1;

FIG. 4 is a top view of the housing with interface panel for a pressure source illustrated in FIG. 1;

FIG. 5 is a front view of the housing with interface panel for a pressure source illustrated in FIG. 1;

FIG. 6 is a bottom view of the housing with interface panel for a pressure source illustrated in FIG. 1;

FIG. 7 is a right side view of the housing with interface panel for a pressure source illustrated in FIG. 1;

FIG. 8 is a left side view of the housing with interface panel for a pressure source illustrated in FIG. 1; and,

FIG. 9 is a top, elevational view taken along lines 9-9 of FIG. 8 of the housing with interface panel for a pressure source illustrated in FIG. 1.

The broken lines in the drawing figures do not form part of the claimed design.

The closely-spaced diagonal shade lines in FIGS. 1, 4, 5, and 9 indicate transparency.
